(57) **CLAIM**

The ornamental design for an electric cart for golf as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a top, front and right side perspective view of an electric cart for golf showing my new design;

FIG. 2 is a top, rear and right side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a top, front and right side perspective folded state;

FIG. 10 is a top, rear and right side perspective view of the electric cart for golf thereof with its scaffolding in folded state;

FIG. 11 is a top, front and right side perspective view of the electric cart for golf thereof with its scaffolding in separated state; and,

FIG. 12 is a top, rear and right side perspective view of the electric cart for golf thereof with its scaffolding in separated state.
